Specification for Design.

Patented Nov. 14, 1916.

Application filed October 2, 1916. Serial No. 123,455. Term of patent 7 years.

To all whom it may concern:

Be it known that I, CHARLES G. STRUBLER, a citizen of the United States, residing at Naperville, in the county of Kane and State of Illinois, have invented a new, original, and ornamental Design for a Scale-Standard, of which the following is a specification, reference being had to the accompanying drawings, forming a part thereof.

In the drawings: Figure 1 is a front view of the design embodying this invention. Fig. 2 is a rear view of the design embodying this invention.

Copies of this patent may be obtained for five cents each, by addressing the "Commissioner of Patents, Washington, D. C."

I claim:

The ornamental design for a scale standard, as shown.

In testimony whereof I have hereunto set my hand at Chicago, Illinois, this 30th day of September 1916.

CHARLES G. STRUBLER.
